UNITED STATES PATENT OFFICE.

GEORGE JENKINS MORGAN AND GEORGE TILLOTSON, OF SHIPLEY, ENGLAND.

COIN-ACTUATED MECHANISM.

SPECIFICATION forming part of Letters Patent No. 664,964, dated January 1, 1901.

Application filed September 22, 1899. Serial No. 731,257. (No model.)

To all whom it may concern:

Be it known that we, GEORGE JENKINS MORGAN and GEORGE TILLOTSON, subjects of the Queen of Great Britain, residing at Shipley, in the county of York, England, have invented certain new and useful Improvements in Coin-Actuated Mechanism, of which the following is a full and complete specification, such as will enable those skilled in the art to which it appertains to make and use the same.

This invention relates to coin-actuated mechanism; and the object thereof is to provide a mechanism of this class whereby various locked devices may be freed through the initial instrumentality of a coin of suitable bulk.

Our invention consists in the construction and arrangement of parts hereinafter described.

In the accompanying drawings we have disclosed our coin-actuated mechanism as applied to a vending apparatus; but it is manifest that the application of the mechanism to a wide range of devices may be made.

Our invention is fully disclosed in the following specification, of which the accompanying drawings form a part, in which like reference characters denote like parts in the several views, and in which—

Figure 1 is a vertical section of a form of apparatus which is adapted for use in the delivery of goods in packet and in other coin-free machinery of the class described. Fig. 2 is a plan view of a detail of Fig. 1, being the part of the coin-slot of the slide by which, with the aid of the coin, the release of the slide from the locking means is effected. Fig. 3 is a detail face view of a pivotal coin-holder which forms a part of our improved construction; Fig. 4, a detail face view of a pivotal coin-support forming a further element of our improved construction, and Fig. 5 a detail plan view of a locking-lever or trigger-arm forming a still further element of our improved construction.

Referring more particularly to the drawings, we have shown at *a* a rectangular case, with the upper surface adapted to form a table or platform 30 for the sliding tray or delivery-slide 31 to travel upon within a portion of the casing. This portion of the casing has again mounted on it a hollow column 32, with usual

glass front, (not shown,) to hold the superimposed packets 33, the bottom of the column being open and communicating with a recess 34 in the slide 31, made of such a depth as to be equal to the thickness of one packet. The slide 31 is normally kept in a closed position by means of a counterbalance-weight 35 or is assisted to close thereby, the weight being suspended by means of a cord 36, attached to a hook 37 and passed over a pulley 38 on the part of the casing at 39, the support 40 of the said pulley also forming a stop for the slide 31. This portion of the apparatus separately considered forms no portion of the invention. The slide 31 is formed with a slot 10 for the passage of a properly-sized coin therethrough to the locking mechanism. This slot 10 is coincident with another slot 17 in a coin-holder *f* below. This slotted holder *f* is pivoted on hinges or projecting pins 19 at its upper edges carried by the frame *a*, and formed through this holder *f*, crossing the line of the middle of the slot 17 of the holder *f*, is an opening 20. Through this opening 20 projects a pin 22 or horn of a slide-pin 41, held in a bearing 42, operated by a pendent or centered arm or lever *g*, which lever *g* in turn is operated by a stud or cross-bar 43, mounted in the slide 31, which is pulled by a suitable handle part 44 to operate the locking and delivery parts.

If the proper coin is not in position, the pin or-horn 22 passes across the slot in the holder *f* unobstructed and strikes against a tilting plate *h*, hinged or centered at 24 on an arm *i* in the inside of the fixed casing centered on a rod 28, projecting from the casing *a*, adjacent to the slotted swing-piece *f*, against which piece 21 lugs 25 from this tilting plate *h* almost come in contact. This slotted swing-piece *f* is at its lower end always connected or in contact with the upper end 26 of the centered trigger-arm, the said upturned end 26 being the lighter one, the other end being counterweighted at 27. This lighter end 26 presses normally upward against or so as to press against or foul a stop-piece 45, engaging a notch 46 on the under side of the delivery-slide 31. Too large a coin is prevented simply by its size from entering by the limited size of the slot. If too small a coin is dropped in, it falls down the fixed slot 10 and through the swing-slot 17, passing between the projecting

lugs or horns 25 of the tilting plate *h*, and not being retained thereby slips into the coin-receptacle in 1, while the locking means is unaffected.

5. If in place of a coin it is attempted to unlock the delivery-slide or equivalent part by the introduction of a washer, such a fraud is prevented by reason of the pin or horn 22 being pushed through the slot of the coin-holder 10 and through the hole in the washer unobstructed, leaving the locking means unoperated.

When the proper coin—say a penny—is in place in the coin-holder or swing-piece *f*, it is retained there by the horns 25 of the tilting plate *h* until the pin or horn 22 of the stem 41, by the pressure of the operating lever or arm *g* pressing against the penny in the slot 17, presses against the slotted piece or coin-holder *f* and depresses the trigger-arm *i* at 21. After tilting said trigger-arm *i* free of the stop 45 the stop 45 drops clear of the slide 31 and the parts are free for use to deliver the goods or otherwise perform their function. As soon 25 as the parts have been moved to a certain point, the coin, being released from its supports, falls into the coin-receptacle below. As soon as the slide is released from use, it is replaced in its closed position and the fastening 30 parts are replaced in position ready for reuse.

We do not limit ourselves to the specific construction and arrangement of parts herein specified, but reserve the right to vary the same within the scope of our invention.

35 Having fully described our invention, we claim as new and desire to secure by Letters Patent—

1. In an apparatus of the class described, a selective compartment 34 for the quantity being delivered, a slide 31, a latch 43, a locking arm *g*, controlling a detective bolt 41, cooperating with a coin-holder *f*, and a tilting plate *h*, mounted on and operating a counterweighted locking-lever *i*, and a bolt or stop 45, engaging a stop or recess in the delivery-slide 31.

45 2. In an apparatus of the class described, a coin-entrance slot, a locking-lever, a stop which said locking-lever normally engages, a pivoted member provided with a coin-receiving slot which normally registers with said coin-entrance slot, said pivoted member being provided with a transverse aperture which passes through said coin-receiving slot, a pivoted coin-support, arranged adjacent said transverse aperture, a projection which normally enters said aperture, and means for operating said projection, substantially as shown and described.

60 3. In an apparatus of the class described, a locking-lever, a movable stop which said locking-lever normally maintains in operative position, a movably-mounted coin-holding member which operates in connection with said locking-lever, and is provided with a coin-receiving aperture, and with a transverse aperture passing therethrough, a movable coin-

70 support arranged adjacent said movable coin-holding member, and means arranged to normally enter said transverse aperture, substantially as shown and described.

4. An apparatus of the class described, comprising a movable delivery-slide, a movable stop device which normally engages and locks the same, locking devices which normally maintain said stop device in engagement with 75 said delivery-slide, a pivoted coin-holder which operates at its free end in connection with said locking devices to free said movable stop device, said coin-holder being provided with a coin-receiving slot and with 80 a transverse slot which communicates therewith, a coin-support pivotally connected with said locking device and arranged adjacent said coin-holder and normally projecting beneath said coin-receiving slot, and a movably-mounted projection which is arranged to enter said transverse slot, said movable projection being operatively connected with said delivery-slide, substantially as shown and described.

90 5. An apparatus of the class described, comprising a movable delivery-slide, a movable stop device which normally engages and locks the same, locking devices which normally maintain said stop device in engagement with 95 said delivery-slide, a pivoted coin-holder which operates at its free end in connection with said locking devices to free said movable stop device, said coin-holder being provided with a coin-receiving slot and with a 100 transverse slot which communicates therewith, a coin-support pivotally connected with said locking device and arranged adjacent said coin-holder and normally projecting beneath said coin-receiving slot, means for normally retaining said delivery-slide in retracted position, and a movably-mounted projection which is arranged to enter said transverse slot, said movable projection being operatively connected with said delivery-slide, 110 substantially as shown and described.

105 6. In an apparatus of the class described, a delivery-slide, means for normally maintaining said delivery-slide in retracted position within the casing, a pivoted stop which 115 is arranged to normally engage said delivery-slide and maintain the same in retracted position, a locking-lever which operates in connection with said stop, a coin-holder pivoted within said casing and provided with a coin-receiving slot which normally registers with a coin-slot in said casing, said coin-holder being provided with a transverse slot which passes through said coin-receiving slot, a coin-support pivoted adjacent said coin-holder and 125 normally projecting beneath the coin-receiving slot therein, said coin-holder being arranged to engage at its lower end and operate in connection with said locking-lever, a support pivoted in said casing and carrying a 130 projection arranged to enter said transverse slot in said coin-holder, the last-named sup-

port being arranged to operate in connection with said delivery-slide, substantially as shown and described.

7. In an apparatus of the class described, 5 a delivery-slide, a pivoted stop which is arranged to normally engage said delivery-slide and maintain the same in retracted position, a locking-lever which operates in connection with said stop, a coin-holder pivoted within 10 said casing and provided with a coin-receiving slot which normally registers with a coin-slot in said casing, said coin-holder being provided with a transverse slot which passes through said coin-receiving slot, a coin-support 15 pivoted adjacent said coin-holder and normally projecting beneath the coin-receiving slot therein, said coin-support being ar-

ranged to engage at its lower end and operate in connection with said locking-lever, a support pivoted in said casing and carrying a 20 projection arranged to enter said transverse slot in said coin-holder, the last-named support being arranged to operate in connection with said delivery-slide, substantially as shown and described.

In testimony that we claim the foregoing as our invention we have signed our names, in presence of the subscribing witnesses, this 17th day of August, 1899.

GEORGE JENKINS MORGAN.
